UNITED STATES PATENT OFFICE

JOHN CURTIS STATION, OF ATLANTA, GEORGIA, ASSIGNOR TO THE COCA-COLA COMPANY,
OF ATLANTA, GEORGIA, A CORPORATION OF DELAWARE

COOLING COIL

Application filed March 19, 1930. Serial No. 437,183.

The invention relates to cooling coils and has as an object the provision of a plurality of coils arranged for circulation of refrigerant in certain of said coils and a liquid to be cooled in other of said coils and having means for ready heat transfer from one coil to the other for refrigeration of the liquid.

It is a further object of the invention to provide a cooling coil which may be utilized to refrigerate a liquid circulating in a coil adjacent a coil in which a refrigerant is circulated and to also utilize the refrigerating coil for refrigeration of a receptacle or a liquid therein.

Further objects of the invention will appear from the following description when read in connection with the accompanying drawings showing an illustrative embodiment of the invention and wherein:—

Fig. 1 is a plan view;
Fig. 2 is an end view; and
Fig. 3 is a side view from the right of Fig. 1.

As shown the device comprises a tube 10 which in the form shown has an inlet at 11 from a source of liquid supply not shown and which passes about three sides of a rectangle and being supplied with a return bend 12 returns about the same three sides of the rectangle. The tube is then dropped to a lower level as by means of a bend 13 and again passes about the three sides of the same rectangle but upon the inner bank of tubes, whereupon by means of a bend 14 the tube is passed to the outside of the bank of tubes in the rectangle, finally reaching the outlet 15.

A tube 16 for refrigerant extends from an inlet at 17 over a path similar to that of the tube 10 but initially passes upon the inner bank of tubes in the rectangle to the bend 18, returning in the outer bank to the bend 19, whereupon the tube 16 passes to a lower level, retraces its path, first in the outer bank of the tubes to the bend 20 transferring it to the inner bank, whereupon the tube extends about the rectangle to the outlet 21 for refrigerant. The tubes for liquid and for refrigerant are thus alternated in the tiers and banks and the warmest liquid is adjacent the coolest refrigerant.

To transfer heat from the liquid tube to the refrigerant tube there are shown a plurality of fins in the form of plates 22 which are in close contact with the walls of the tubes and which additionally assist in maintaining the spacing of the tubes. There is thus provided an exceedingly easy exchange of heat between the liquid and the refrigerant.

If desired the coil thus provided may be housed in a receptacle indicated diagrammatically by dot and dash lines at 23 and the respective inlets and outlets of the tubes are indicated as passing to the exterior of such a receptacle. If so used water or other liquid may be placed in the receptacle and bottles or other objects to be cooled may be immersed in the water within the open space of the rectangle whereupon the fins are operative not only to transfer heat from the liquid to be cooled in the coil but also to transfer heat from liquid in the receptacle in exterior contact with the fins, to the refrigerant coil.

It is obvious that the tubes could be caused to pass across the side of the rectangle at present shown open, or could be made circular instead of rectangular in outline without departing from the spirit of the invention, the important element being the transfer of heat between tubes by means of plates in contact with the walls of both and the arrangement of the various tiers of the tubes containing liquid to be cooled alternately with the tiers of the tubes containing the refrigerant.

The formation of the coil to conform to sides of a rectangle has certain advantages by reason of which this form is preferred. When this form is used the assembly may be made to fit into a rectangular container having the center open for reception of articles, as bottles of soft drinks, which articles may be cooled by liquid in which the articles are immersed. Also by virtue of the rectangular form the adjacent plates may be parallel with each other and normal to the tubes, thus enabling a more efficient spacing.

It is preferred to form the tubes of copper for its ready transfer of heat and the

plates or fins of aluminum, these materials being found efficient for use.

The refrigerant utilized may be expanding sulphur dioxide, carbon dioxide, or any other well known refrigerant and the inlet to the refrigerant coil indicated at 17 may be connected to the output of a compressor and the outlet 21 of this coil may be connected to the intake of the same compressor, which 10 compressor forming no part of the invention is not shown in the drawings.

When used in the dispensing of soft drinks, bottled drinks may be placed in a receptacle such as indicated at 23 immersed in cold water therein and water, plain or carbonated for use at a fountain, may be circulated in a pipe 10.

Minor changes may be made in the physical embodiment of the invention within the 20 scope of the appended claims without departing from the spirit of the invention.

What is claimed is:

1. A cooling coil comprising in combination, a liquid tube extending about a plurality of sides of a rectangle and returning about said sides in a path parallel with and spaced inwardly from its first extension, a refrigerant tube parallel with and spaced vertically from said liquid tube, and plates 30 having openings occupied by said tubes, said plates contacting with the walls of said tubes whereby to facilitate heat transfer between said tubes.

2. A cooling coil comprising, in combination, a liquid tube extending about a plurality of sides of a rectangle in horizontally spaced parallel turns and in a plurality of vertically spaced portions, a refrigerant tube having portions alternating vertically with 35 said liquid tube portions and turns parallel with said liquid tube turns and a plurality of spaced parallel plates having openings through which said tubes pass in each of said turns and portions whereby to facilitate heat transfer between said tubes.

3. A cooling coil comprising, in combination, a liquid tube coil formed with a plurality of straight horizontally spaced parallel portions extending along a plurality of the 50 sides of a rectangle, said portions also comprising a plurality of vertically spaced portions parallel with said horizontally spaced portions and said portions connected to form a single conductor for liquid, a refrigerant 55 tube having portions parallel with, spaced from and alternating vertically with the turns of said liquid tube and likewise forming a single conductor for refrigerant and 60 spaced vertical plates of heat conducting material having openings through which each of said tube portions pass whereby to hold said coils in assembly and to assist heat transference between said tubes.
